ENGINE ARRANGEMENT IN AIRCRAFT

Walter Blume, Brandenburg-on-the-Havel, Germany, assignor of one-half to Arado Flugzeugwerke Gesellschaft mit beschränkter Haftung, Brandenburg-on-the-Havel, Germany

Application December 23, 1938, Serial No. 247,518
In Germany January 6, 1938

5 Claims. (Cl. 244—55)

This invention relates to an arrangement of the engines in aircraft, more particularly of such engines in which there is provided for two rows of cylinders a common crank-shaft arranged in the direction of the longitudinal axis of the fuselage.

It is already known so to fit into an aeroplane an engine with opposed cylinders that the engine lies mainly in the interior of the fuselage with parts of its cylinders projecting into the interior of the supporting wings. With this arrangement it is possible to dispense with a gondola for reception of the engine so that such aeroplanes can be constructed with a low air resistance. This arrangement has however only heretofore been possible in single-engine aircraft. In larger aeroplanes and especially in high-speed machines which require two engines or two groups of engines for developing the necessary power, it is very difficult to fit the engines within the aeroplane without deforming the profile by addition of gondolas or gondola-like structures.

These drawbacks are avoided by the present invention according to which each engine is arranged partly within the fuselage and partly within the adjacent supporting wing, the engines being operatively connected by means of transmission mechanism with air-screws mounted externally of the fuselage.

With a V arrangement of the cylinders, the two engines or the two groups of engines may be so fitted into the aeroplane that both cylinders or rows of cylinders are located in the interior of the fuselage while the crank cases are located in the roots of the supporting wings.

If with a ninety-degree engine, in which each cylinder is located at right angles to the associated cylinder, or each row of cylinders is located at right angles to the other row of cylinders, then it may be advisable to fit both the crank case as also one cylinder or one row of cylinders of each engine in the fuselage and to allow the other cylinder or row of cylinders to project into the root of the appertaining wing.

If there are used engines with cylinders in opposed relation, that is according to the so-called "boxer" arrangement, then suitably the engine crank case is shifted into the root of the respective wing. One row of cylinders is then fitted in the wing and the other row of cylinders is fitted in the fuselage. Thereby there is effected close adaptation of the dimensions of the engines to the dimensions of the several parts of the aeroplane, as the crank case with its relatively large dimensions is fitted in the thickest

part of the supporting wing, that is, in the root, while one cylinder projects as a structural unit of less thickness into the wing proper.

Three embodiments of the invention are illustrated in the accompanying drawings in which Figs. 1 to 3 are diagrammatic cross sectional views of an aeroplane structure; Fig. 4 is a plan of Fig. 3.

In the embodiment according to Fig. 1 there are provided two engines 1, 2 each with its cylinders in V relation. The cylinders are arranged within the fuselage and the crank cases are arranged in the roots of the respective wings.

In the modification according to Fig. 2, there are used two ninety-degree engines in which the rows of cylinders of each engine are at right angles to one another. The crank case and one row of cylinders of each engine are arranged in the fuselage, and the other row of cylinders of each engine is arranged in the root of the respective wing.

Fig. 3 shows a machine equipped with two engines with opposed cylinders, in so-called "boxer" relation. The crank cases are arranged in the roots of the respective wings. One row of cylinders of each engine is arranged in the respective wing and the other row of cylinders is arranged in the fuselage.

The two engines 1, 2 are disposed symmetrically at opposite sides of the vertical central plane of the fuselage. The crank shafts designated 1', 2' drive by way of bevel gears 9, 10 transverse shafts 7, 8 which actuate by way of pairs of bevel gears 11, 12 air-screws 13, 14 arranged at starboard and port, respectively, with respect to the fuselage. As shown in Fig. 4, the engines 1, 2 are arranged between the spars 3, 4 and 5, 6 of the two supporting wings.

In the examples illustrated, each engine is coupled only with the air-screw adjacent thereto. Both engines may, however, act on the same air-screw, with the interposition of gearing common to the two engines, whereby it is ensured that both air-screws will rotate at the same speed.

To increase the efficiency it is possible to arrange two engines at each side, that is four engines in all, constituting two pairs of engines of which one engine of each pair is located behind the other in the direction of the axis of fuselage, said engines being coupled together.

I claim:

1. In an aeroplane, the combination of a fuselage, supporting wings having roots joined to said fuselage, air-screws mounted exteriorly of said fuselage, engines each comprising at least two

- cylinders and a crank shaft common to said cylinders, each of said engines being arranged partly within said fuselage and partly within a supporting wing, and transmission mechanism 5 coupling said shafts to said air-screws.
2. In an aeroplane, the combination claimed in claim 1 in which the engines have cylinders in V relation located in the fuselage and crank cases located in the roots of the wings.
- 10 3. In an aeroplane, the combination claimed in claim 1 in which the engines each have rows of cylinders in V relation, of which one row and the engine crank case are located in the fuselage, and the other row is located in the root 15 of a wing.

4. In an aeroplane, the combination claimed in claim 1 in which each engine has a crank case and rows of opposed cylinders, of which one row of cylinders is located in a wing and the other row located in the fuselage, each of said engines 5 having a crank case located in the root of a wing.

5. In an aeroplane, the combination claimed in claim 1 in which each engine has a crank case and rows of opposed cylinders of which one row 10 of cylinders and the crank case are located in a wing and the other row of cylinders is located partly in the root of the wing and partly in the fuselage.
